UNITED STATES PATENT OFFICE.

JULIAN P. CONNER, OF COMO, MISSISSIPPI.

TOY PISTOL OR GUN.

1,263,859.

Specification of Letters Patent. Patented Apr. 23, 1918.

Application filed February 9, 1918. Serial No. 216,416.

To all whom it may concern:

Be it known that I, JULIAN P. CONNER, residing at Como, in the county of Panola and State of Mississippi, have invented a new and useful Toy Pistol or Gun, of which the following is a specification.

The present invention has for an object to provide a mechanism or device of this character adapted to discharge one or more caps, 10 or the like upon a single or continuous operation of a trigger or similar operating element.

Another object of this invention is to provide a cap exploding device of this character 15 which may be economically constructed from stamped metal; which comprises relatively few parts; and which may be mounted in a frame simulating a pistol, gun, or other desired type of firearms.

20 The above and various other objects and advantages of this invention will be in part described and in part understood, from the following detailed description of the present preferred embodiment, the same being 25 illustrated in the accompanying drawing, wherein:

Figure 1 is a longitudinal section through a toy pistol constructed according to the present invention.

30 Fig. 2 is an enlarged transverse section taken through the same on the central axis thereof.

Fig. 3 is a fragmentary, enlarged, perspective view of the hammer disk and the 35 firing member associated therewith.

Fig. 4 is a perspective view of a slightly modified form of the device constructed to simulate a rapid firing gun.

Referring to the drawing, and first to the 40 form shown in Figs. 1, 2, and 3, 10 designates a supporting or body plate constructed of sheet metal adapted to be arranged in upright position within a gun frame 11 which, as shown in Fig. 1, may simulate a 45 pistol.

The plate 10 carries intermediate its ends a transverse shaft or pivot 12 which is seated at one end in the plate and at its other end in an overturned spaced flange 13 extending 50 from one of the longitudinal edge portions of the plate. A disk 14 mounted on the pin 12, is adapted to turn, and is provided with a circular row of spaced apart lugs 15 stamped from the plate at its peripheral 55 edge and extending laterally from the disk. The lugs 15 extend substantially radially

from the disk and form anvil portions adapted to be engaged by the trigger and by the firing device as hereinafter pointed out.

A trigger 16 is mounted at one end on 60 the pin 12 concentric to the disk 14 and is adapted to swing in a path longitudinally of the plate 10. The trigger 16 is preferably arranged between the plate 10 and the disk 14 and is provided, between its ends 65 with a pawl or spring catch 17 at its side toward the disk, the pawl extending in one direction edgewise of the trigger and being shouldered to engage the lugs 15 and advance the disk when the trigger is moved in 70 one direction. A spring 18 is carried by the plate 10 between the same and the disk and has a free end bearing against the trigger 16 to urge the same for movement toward one end of the plate, which end will be hereinafter referred to as the forward end of the 75 plate.

A transverse pin 19 is carried between the rear end of the plate 10 and the flange 13 adapted to support a rolled cap strip 20, 80 the latter being carried over the top of the disk 14 and supported in flat position against the under side of the top of the flange 13 by the lugs 15. The stamping of the lugs 15 forms slots 21 in the periphery 85 of the disk into which may project the caps of the strip for insuring the uniform advancement of the strip by the turning of the disk. A stop or catch 22 is suitably mounted upon the plate 10 in the path of the 90 lugs 15 to engage the same and hold the disk from turning backward when the trigger 16 is moved forward by its spring 18.

A firing member 23, in the form of a flat spring, is mounted at one end upon studs or 95 pins 24 carried upon the forward end of the plate 10 and extends backward toward the disk 14 and is provided with a downwardly offset nose 25 lying in the path of the lugs 15 and adapted to be consecutively engaged 100 thereby and sprung downward away from the top of the flange 13. The strip 20 is threaded over the disk 14 and over the firing member or spring 23 and is normally held pressed against the flange 13 by the spring. 105 The nose 25 is of a length adapted to release the spring from the adjacent lug 15 before the next adjacent lug is advanced into the path of the nose, thus admitting the free snapping of the spring against the strip 20 110 to explode the adjacent cap carried by the strip.

The lower edge of the plate 10 has a guide flange 26 turned beneath the flange 13 and provided with a longitudinal slot 27 through which the lower end of the trigger 16 passes, the ends of the slot limiting the reciprocating movement of the trigger, and the slot being of sufficient length to admit the retraction of the trigger sufficient to advance two or more of the lugs 15 against the firing 10 spring 23. The length of the stroke of the trigger 16 may of course be varied to discharge any number of the caps consecutively within the range of the mechanism.

As shown particularly in Fig. 3 the 15 spring strip 23 may be returned upon itself at its free end to form an impact face 28 for more forcibly striking the adjacent cap when the spring is released. The supporting lug 32 is inturned from the body plate 20 beneath the flange and between the disk 14 and the firing member 23 for holding the strip from looping downward as it is pushed from the disk 14 over the firing member.

In the modified form illustrated in Fig. 4 25 the disk may be mounted upon an operating crank handle 29 adapted to be continuously turned for effecting the continuous rotation of the disk and the consequent continuous discharge of the caps carried upon a cap strip 30 fed through the mechanism in the manner disclosed in Fig. 1. This arrangement is particularly adapted for application to a frame 31 simulating a rapid firing gun.

It is of course understood that various 35 modifications and changes may be made in the details of construction and design to adapt the device for discharging practically any number of caps upon the operation of the operating member, and for application 40 to frames of various designs, the changes and modifications being restricted by the scope of the following claims.

What is claimed is:

1. In a toy pistol or gun, the combination 45 of a plate, a disk pivoted upon the plate and having laterally extending lugs, a support on the plate for sustaining a cap strip with the latter engaging over the disk and the lugs, a spring firing member carried by the 50 plate and normally bearing against said strip and provided with a nose lying in the path of said lugs, and means for turning said disk to consecutively engage the lugs with said firing member to retract the same, 55 said member being adapted to snap past said lugs and strike the caps on said strip.

2. In a toy pistol or gun, the combination 60 of a support, a rotary member on the support provided with transverse lugs, sustaining means on the support for carrying a cap strip with the end of the strip passing over said member, means for rotating the mem-

ber, said lugs being adapted to engage the strip for advancing the same, and a firing member carried by the support for engagement with said lugs for actuating the firing member to discharge the caps on said strip. 65

3. In a toy pistol or gun, the combination 70 of a support, a strip carrying means on the support, cap firing means on the support, actuating means on the support, and a single rotary member adapted to engage the strip and both of said means for holding, advancing and firing the strip.

4. In a toy pistol or gun, the combination 75 of a support, strip carrying means on the support, cap firing means on the support, actuating means on the support, and a disk having lugs stamped and projecting laterally from the disk for engaging said strip to support and feed the same and adapted 80 to engage both of said means for advancing and firing the strip.

5. In a toy pistol or gun, the combination 85 of a support, a disk pivoted on the support and having a circular row of spaced lugs laterally extending therefrom, means on the support for maintaining a cap strip against the disk and the lugs, a firing member on the support in the path of the said lugs for intermittently exploding the caps of the strip, and means also in the path of said lugs for 90 engaging the same and for turning the disk to advance the cap strip and actuate the firing member. 95

6. In a toy pistol or gun, the combination 100 of a support, a sheet metal disk pivoted on the support and having a row of spaced lugs stamped extending laterally from the peripheral portion of the disk, means on the support for retaining a cap strip in contact with the disk and lugs to advance the strip, means for exploding the caps actuated by the disk, and means for turning the disk. 105

7. In a toy pistol or gun, the combination 110 of a plate overturned at one edge to form a spaced flange and having a flange at its other edge arranged beneath the first flange, a disk pivoted between the plate and the first flange and having lugs stamped laterally therefrom 115 in a peripheral row, a pin carried upon one end of the plate for supporting a rolled cap strip with the end of the strip passing over said lugs, a firing spring mounted upon the plate at one side of the disk to receive said strip thereover and having a nose projecting into the path of said lugs, and a trigger pivoted on the plate and having a pawl adapted to engage said lugs for advancing the disk in one direction and being normally urged 120 in the opposite direction, said second flange engaging the trigger to brace and limit the throw of the same.

JULIAN P. CONNER.
